UNITED STATES PATENT OFFICE.

ARTHUR J. KINCH, OF OGDENSBURG, NEW YORK, ASSIGNOR OF ONE-HALF TO JOHN COTTER, OF CHICAGO, ILLINOIS.

HOSE-REEL.

1,147,327.

Specification of Letters Patent. Patented July 20, 1915.

Application filed March 30, 1914. Serial No. 828,151.

To all whom it may concern:

Be it known that I, ARTHUR J. KINCH, a citizen of the United States, residing at Ogdensburg, in the county of St. Lawrence 5 and State of New York, have invented certain new and useful Improvements in Hose-Reels, of which the following is a specification.

This invention relates to improvements in 10 hose-reels, and has for its object to provide a novel and simple device of the class, which is particularly adapted for use on ships, in warehouses, public buildings, and the like, as a protection against fire.

15 A further object is to provide a hose-reel having a hollow hub which is intended to be connected directly to and supported by a water-pressure supply-pipe, the said hub rotatably supporting all the other parts of the 20 reel, and also the hose.

A further object is to provide a valve in 25 the hub of the reel, for controlling the passage of the water from the supply-pipe to the hose. And a further object is to provide a hose-reel, wherein by the unwinding of 30 the hose, the valve is automatically opened and the water begins to flow through the nozzle without having to first unwind the hose, and then turn on the water, as by the old way.

The various features and parts of the invention will be understood from the detailed description which follows, and by reference to the accompanying drawings, in which—

35 Figure 1 is a side elevation of the complete device; showing the hose wound upon the reel ready for use. Fig. 2 is a vertical section, taken on line 2—2 of Fig. 3. Fig. 3 is a central horizontal section, taken on line 40 3—3 of Fig. 1; showing by full and dotted lines the closed and open positions of the valve. Fig. 4 is a detail view of the valve. Fig. 5 is a perspective view of the hub of the reel.

45 In the drawings, my automatic hose-reel comprises the following parts:

2 represents a hollow hub, preferably made of brass, having one end 3 contracted and externally threaded for screwing into a 50 water-pressure supply-pipe (not shown). Adjacent the end 3, the hub is provided with a hexagonal portion to receive a wrench for applying and detaching the reel. The opposite end 4 of the hub is a plain cylinder, 55 which is internally threaded to receive a

plug 5. About midway between the ends of the hub is a valve-seat 6, and adjacent the said seat the cylindrical portion 4 is perforated, as at 7, 7, to allow the water to escape from the hub. 60

8 represents a valve disposed in the cylinder 4 concentric to the seat 6. The valve 8 is mounted on a stem or rod 9, the back of the valve having a way 10 formed by parallel guides 10', to receive the flanged end 9' of the stem. This form of connection permits the stem 9 to revolve when opening and closing the valve, without rotating the valve and unnecessarily wearing the valve 65 or seat. The stem 9 is externally threaded at 11, near the valve, and these threads engage a threaded hole in the plug 5. The valve 8 is also provided with a series of guide-lugs 12, which bear against the inner wall of the cylinder 4, for holding the valve 70 concentric to the seat 6. 75

13 represents a sleeve or outer hub which surrounds the cylindrical portion 4 of the hub 2, the opposite ends of the said sleeve having annular flanges 14 and 15, which support the spokes 16 of the reel. The sleeve 13 is provided with an internal flange 17 which engages an annular shoulder 18 of the hub 2, for limiting the insertion of the latter in the sleeve. The sleeve and hub are 80 held together by a gland-ring 19, which is secured to the flange 14 by bolts or screws 19', and also by an annular cap 20, which is secured to flange 15 at the opposite end of the sleeve, by bolts or screws 20'. To prevent the leakage of the water around the hub 2, packing rings 21 and 22 are positioned so as to be compressed by the gland 19 and the cap 20, as shown in Fig. 3. The sleeve 13 is provided intermediate the flanges 85 14 and 15 with an external circumferential rib 23 for forming an annular water passage 23', which surrounds the hub 2, and receives the water coming from the supply-pipe by way of the valve 8, and the holes 90 in the hub, whenever the valve is opened. 95

At one side of the hub the rib 23 is spiral-shaped, as at 24, for directing the water from the passage 23' to an outlet 25, which is threaded to receive one end of a bushing or coupling 26, which has a flange seating against a packing 26'. The opposite end of the bushing 26 is arranged to telescope the hose 27, which may be secured thereto by any suitable means. The hose 27 may be 100 105 110

any length or size, and it is intended to remain coupled to the sleeve 13, and may be wound up (see Fig. 1) or unwound (see Fig. 2), the same as the devices now in use. The 5 free end of the hose is preferably fitted with the usual nozzle 28.

The valve stem 9 passes through a central perforation 29 in the cap 20, which is enlarged and threaded to receive a gland-nut 10 30, the latter compressing a packing 30' for preventing the leaking of the water around the stem. The valve-stem 9 next passes loosely through a bridge 31, which is mounted on the cap 20 and secured thereto by certain of the bolts 20', as shown in Figs. 1 and 15 3. Beyond the bridge 31, the stem 9 is squared, as at 32, to receive and drive a ratchet gear 33, and also a hand-wheel 34, and these are held in place by a nut 35, 20 which is screwed on to the threaded end 36, of the stem.

37 represents a pawl, which is pivoted by a pin 38 to the bridge 31, and is held engaged with the ratchet-gear, by means of a 25 spring 40, which bears against the underside of the handle 41 of the pawl.

The operation of my improved hose-reel is as follows: Assuming that the parts of the reel are in the positions shown in full 30 lines in Figs. 1 and 3, the hose 27 being wound around the sleeve 13, and the valve 8 being closed, which prevents the water from passing from the end 3 of the hub into the 35 chamber 23'. The operator takes hold of the nozzle 28, and starts to unreel the hose, which rotates the sleeve 13 toward the left (see arrow in Fig. 1). The pawl 37 at this time engages the ratchet 33 and compels the 40 valve stem 9 to rotate with the sleeve 13. As soon as the sleeve 13 begins to turn toward the left, the plug 5 being stationary, the same as the hub 2, forces the stem 9 outwardly, which moves the valve away from 45 its seat 6, to the extent shown by comparing the full with the dotted lines in Fig. 3. As the valve stem 9 moves outwardly through the cap 20 and bridge 31, the ratchet wheel 33 also moves out of engagement with the 50 pawl 37 (see dotted lines in Fig. 3). When the ratchet becomes free from the pawl, the 55 valve 8, is then opened to its fullest extent, the stem 9 becomes stationary like the hub 2, and the further unwinding motion of the reel does not strain or injure the threads of either the stem 9 or plug 5. The first slight 60 turning of the sleeve 13, as described, frees the valve 8 from its seat 6, and allows the water to enter the passage 23'. As the unwinding of the hose continues the full, pressure is turned into the hose, and as the operator carries the nozzle away from the reel he may direct the stream upon a fire, or use 65 the water for other purposes. Under the

present construction and arrangement of the reel, the hose is always ready for instant 65 use, and the operator does not have to resort to the usual steps or acts, such as unwinding the hose, connecting it to the faucet or plug, and then turning on the water. In my improved reel, the pressure, is always 70 waiting at the valve 8 ready for the operator to start the unwinding of the hose, which automatically opens the valve and fills the hose. After the hose has done its work it should be rewound on the reel. But before 75 starting to rewind, the operator should tilt the pawl 37 from the full to the dotted line position, shown in Fig. 3. This swings the pawl away from the ratchet 33, and then by turning the hand-wheel 34, in the proper direction, he may close the valve 8, for shutting off the pressure. The rewinding may then be accomplished in the usual way, and whatever water still remains in the hose 80 will escape through the nozzle. When the 85 ratchet wheel has moved toward the full line position, shown in Fig. 3, far enough for the pawl to engage the teeth, the pawl may be allowed to assume its normal (full line) 90 position, and then during the subsequent turning of the valve stem, the pawl will play idly over the ratchet teeth.

Having thus described my invention, what I claim as new and desire to secure by Letters Patent, is—

A hose reel, including a stationary hollow hub adapted for attachment to a source of water supply, said hub having a valve-seat therein, and having an annular shoulder surrounding said seat, a sleeve having spaced 100 flanges for receiving a hose journaled on said hub and having an internal flange engaging the annular shoulder of the hub for preventing longitudinal movement in one direction, said sleeve having a spiral water 105 passage receiving water from the hub, and delivering the water to a hose, a gland-ring interposed between the hub and one end of said sleeve for preventing the longitudinal movement of said sleeve in the opposite direction, a cap mounted on the opposite end of said sleeve, a bridge mounted on the said cap, a valve in said hub reciprocatable toward and from said seat, a stem for operating said valve, said stem journaled in said 110 cap and also in said bridge, a ratchet wheel carried by said stem, and a pawl carried by said bridge for opening the said valve by the revolving of the said sleeve.

In testimony whereof I affix my signature 115 in presence of two witnesses.

ARTHUR J. KINCH.
